Des. 557

Garrettson Smith &
Henry Brown, of Philadelphia, Pa.
Assignors to
North, Chase & North, of Philadelphia, Pa.
Letters Patent No. 557, Dated Apr. 26th 1853.

The schedule referred to in these Letters Patent and making part of the same

To all whom it may concern:

Be it known that we, Garrettson Smith & Henry Brown, of the County of Philadelphia, and State of Pennsylvania, have invented a new and improved design for Portable Ranges, of which the following is a full and exact description, reference being had to the accompanying drawings, making part of this specification, in which

Fig. 1, is a drawing of the front plate & doors.

Fig. 2, is a drawing of the end plate.

Fig. 3, is a drawing of a portion of the hearth plate.

Fig. 4, is a drawing of a portion of the top plate.

The ornamental work is composed of a combination of vines, spear, scrolls, chains, tears, boxes, and mouldings as represented in the drawings.

What we claim as our invention, and desire to secure by letters patent, is the design and configuration of the mouldings and ornamental work, as herein described, forming an ornamental design for a portable range.
